UNITED STATES PATENT OFFICE.

HUBERT F. KRANTZ, OF BROOKLYN, NEW YORK.

ELECTRICAL SWITCH INSTRUMENTALITY.

1,250,324.

Specification of Letters Patent. Patented Dec. 18, 1917.

Original application filed March 13, 1915, Serial No. 14,130. Renewed April 11, 1916, Serial No. 90,159. Divided and this application filed February 12, 1916. Serial No. 77,878.

To all whom it may concern:

Be it known that I, HUBERT F. KRANTZ, a citizen of the United States, and residing at Brooklyn, in the county of Kings and State of New York, have invented a new and Improved Electrical Switch Instrumentality, of which the following is a full disclosure.

This invention is a division of my copending case No. 14,130 filed March 13, 1915, and renewed April 11, 1916, Serial No. 90,159, and its subject-matter is more especially directed to a switch-operating instrumentality so constructed as to harmonize with a simplified arrangement of a panel-board of the type enabling one or more branch-line circuits to be connected or disconnected with the main supply or with bus bars connected therewith.

Among the objects of this invention are, (a) to create a compact few-part switch-moving mechanism conducive to a greatly simplified panel board arrangement; (b) to provide a switch-mechanism especially suitable for direct co-operation with the various branch-line connections; and (c) to provide a switch-mechanism peculiarly well adapted for actuation manually or otherwise from the front face of a panel board and having all parts save the operating handles located out of sight, and designed in a manner simple and durable yet capable of carrying excessive currents and of making very quick breaks.

Other objects will be in part obvious from the annexed drawings and in part indicated in connection therewith by the following analysis of this invention.

This invention accordingly consists in the features of construction, combinations of parts, and in the unique relations of the members and in the relative proportioning and disposition thereof; all as more completely outlined herein.

To enable others skilled in the art so fully to comprehend the underlying features thereof that they may embody the same by the numerous modifications in structure and relation contemplated by this invention, drawings depicting a preferred form have been annexed as a part of this disclosure, and in such drawings, like characters of reference denote corresponding parts throughout all the views of which:—

Figure 1 is a side elevational view of a

switch mechanism constructed in accordance with this invention and showing the same applied to a switch board, parts of the view being shown in section for better disclosing the arrangement.

Fig. 2 is a sectional view taken substantially upon the plane of line II of Fig. 1.

Fig. 3 is a view similar to that shown in Fig. 1, but illustrating the switch mechanism in the "off" position, and

Fig. 4 is a perspective view of a switch of this invention showing the same in operative position upon the rear side of the switch board.

Continuing now, by way of a more detailed analysis of the primary characteristics of this invention, A designates a board of insulating material, as of slate, marble or the like, which forms the front exposed face of the panel carrying the operating handles and on the rear-side of which are mounted the various parts arranged in accordance with this invention. A branch line contact carrier B is spaced from the rear surface of the board and supports a plurality of branch line contacts, 1, 2 and 3 together with suitable fuses 4, 5 and 6 which are connected with branch line wires 7, 8 and 9, said wires being supported by the carrier B.

Bus bars, x, y and z are supported at the rear surface of the board A in spaced relation to each other one for each of the contacts 1, 2 and 3.

The switch blades G, G' and G'' are supported by the carrier C which is made up of a strip of sheet metal bent to form opposite clamp plates 25 and 26 between which the switch blades are clamped in spaced substantially parallel relation. The carrier extends transversely of the blades substantially midway of their length as clearly shown in the drawings and is provided with pivot extensions 10 and 11 at its opposite ends by means of which it is mounted in suitable supporting plates 12 and 13 to swing the switch blades in unison to cause their opposite ends to move into and out of contact with the bus bars and branch line contacts respectively.

Suitable insulating members 14 are provided between the switch blades and the clamp plates for insulating the switch blades from each other and from said clamp plates.

The supports 12 and 13 are preferably in-

dependently formed and attached to the base board so that they may be employed for supporting switch blade carriers of varying lengths.

- 5 The switch blades are flexible so that when pressed into engagement with the bus bars and branch line contacts they are caused to flex to a greater or less extent and thereby to store energy within themselves tending 10 to return the carrier to the "off" position. A coil spring 28 has one of its ends 17 fixed to the extension 10, as by being received within a transverse opening 18, and has its other end, as 19 fixed to the support 12 as 15 by being received within an aperture 20. This spring is arranged and tensioned to urged the carrier and switch blade into full "off" position.

The ends of the clamp plates forming the 20 carrier C adjacent the support 12 are bent at right angles as at 15 so as to constitute a laterally extending arm for the carrier by means of which the carrier may be swung from an operating handle I at the front of 25 the board. The bent ends of the plates are spaced apart to receive a link d which is connected thereto by a pin e, said link constituting one element of a toggle. The other element of the toggle is made up of two 30 links f and g which are pivotally connected at one end to the support 12 by a pin a and at the other end to the free end of the link d by a pivot pin b constituting the knuckle of the toggle. The parts are so proportioned 35 that when the links d and e have assumed the position shown by Fig. 1, (the pivot b being slightly overthrown beyond the center line a to e), the switch blades G, G' and G" will press tightly against their respective contacts so as to spring the parts as shown 40 in Fig. 1. A suitable means for limiting movement of the toggle in its made and broken positions such as the stop pins 30 and 31 may be provided, or the supporting 45 plate 12 may be formed with an arcuate slot 21 into which one end of the pivot pin b extends, the opposite end walls of the slot constituting stops against which the pin b engages. This arrangement is combined with 50 a "lost motion" operating-device constructed in such a manner that the instant the toggle is broken, the "lost motion" will provide for a free and unimpeded continuation of the movement of the toggle in its collapsing direction under the impulse of the 55 spring 28, augmented momentarily at the beginning of the throw by the reaction of the flexed-blades G, G' and G". The effect of this is to cause an exceedingly abrupt 60 break, since the spring tension is greatest a few degrees prior to the actual disconnecting station and when the greatest force is needed to overcome the momentum or inertia of the parts. The spring 28 will complete the throw of the parts and bring the 65

toggle into its collapsed state with the switch blades in an intermediate position substantially as shown in Fig. 3.

The lost-motion device may embody a member H providing a portion h serving as 70 a contact-surface adapted to advance and press against pivot b, or other suitable part associated with the toggle, so that after its contact has been established, the toggle will positively be moved so that the pin b may 75 cross the centerline and be able thereupon to travel freely and without restriction in the toggle-collapsing direction. Preferably in unitary relation with the member H, is a second contact-surface k adapted to be 80 brought into contact with a part associated with the toggle so that, by the movement of the member H, the toggle may be swung from its collapsed position into the unbroken position shown by Fig. 1. These 85 contact-surfaces h and k are arranged or spaced with such relation to the parts with which they coöperate as to provide sufficient idle motion in the part H so that when the surface h unbreaks the toggle, the surface k will not impede its collapsing. The member H may, in turn, be actuated in any suitable manner, manually or otherwise, as by means of a hand-lever I pivoted at 32 to a support secured to the outer face of the insulating-board A and pivoted at 34 or otherwise connected to the part H so that in one position of the handle I, say in its vertical, the toggle will be closed to establish contact through the switch-blade, and in its other position the toggle will be broken to disestablish the electrical connection.

Without further analysis, the foregoing will so fully reveal the gist of this invention that others can by applying current 105 knowledge readily adapt it for various applications without omitting certain features that, from the standpoint of the prior art, fairly constitute essential characteristics of the generic or specific aspects of this invention, and therefore, such adaptations should and are intended to be comprehended within the meaning and range of equivalency of the following claims.

Having thus revealed this invention, I 115 claim as new and desire to secure the following combinations of elements, or equivalents, thereof, by Letters Patent of the United States:

1. In a switch mechanism for dead-face 120 boards, the combination comprising a double ended switch member which is pivotally mounted intermediate its ends to swing said ends simultaneously for disposing them into and out of engagement with suitably spaced 125 contact members, supporting means for the switch member of a character to support the switch member from one surface of a suitable board with the pivotal axis arranged so that one end of the switch member will 130

- swing outwardly away from a suitable contact which may be carried by the adjacent surface portion of said board while the opposite end of the switch member swings inwardly toward the board and out of engagement with a contact which may be spaced from the board, an operating arm fixed to the switch member projecting laterally therefrom in a plane substantially at right angles to the board by means of which the switch member may be swung, toggle means for swinging said arm comprising a pair of links pivotally connected together and to said support and arm to oscillate substantially in said mentioned plane, together with an actuating member associated with the toggle also movable in said mentioned plane adapted to extend from the toggle through the board for actuating the toggle from the opposite side of the board.
2. In combination, a plurality of switch blades, a carrier for the switch blades comprising a member extending transversely of the switch blades and having means to retain the switch blades fixed thereto to extend laterally therefrom spaced apart along the length of the carrier, pivotal extensions provided at the opposite ends of the carrier by means of which the carrier may be pivotally supported to provide means permitting the several switch blades to swing in unison into and out of engagement with appropriately arranged contact members, supporting means for said extensions, a spring for swinging the carrier and blades in one direction, one of said pivot extensions having a transverse aperture formed therein receiving one end of the spring, the opposite end of the spring engaging the support, and means operatively connected with the carrier to swing the same at will against the tension of the spring in the other direction.
3. In combination, a plurality of switch blades, a carrier for the switch blades comprising opposite clamp plates from between which the switch blades laterally extend, said clamp plates holding the switch blades spaced apart along the length of the clamp plates, insulating means insulating the switch blades from each other and from the clamp plates, pivotal extensions provided at the opposite ends of the clamp plates by means of which the carrier may be pivotally supported to provide means permitting the several switch blades to swing in unison into and out of engagement with appropriately arranged contact members, supporting means for said extensions, means engaging between one of said extensions and said supporting
- means for urging said carrier in one direction, and means operatively connected with the carrier to swing the same at will in the other direction.
4. A switch mechanism comprising a pivotally mounted switch blade carrier, a support therefor, a flexible switch blade carried by the carrier extending laterally from the pivotal axis thereof, said switch blade having its outer end adapted to be swung into and out of surface engagement with a suitable contact member, an operating arm also extending laterally from the pivotal axis of the carrier by means of which the carrier and switch blade may be swung, a toggle connected with said arm movable into made and broken positions for actuating said arm, the switch blade being adapted to be flexed against the contact when the toggle is made, means to move the toggle from made position and permitting unobstructed movement of the toggle to full broken position, the energy in the switch blade being effective when the toggle is moved out of made position for moving the switch blade in a direction away from the contact, and a spring engaging between said support and a portion of said carrier for insuring swinging movement of said carrier and switch blade to full off position.
5. A switch mechanism comprising a pivotally mounted switch blade, a supporting plate therefor, a laterally projecting arm fixed to the switch blade by means of which the switch blade may be swung to dispose its end into and out of engagement with a suitable contact member, a toggle connected between the supporting plate and said arm for swinging said arm, said toggle comprising a pair of links pivotally connected to said supporting plate and to said arm and being pivotally connected together by a pivot pin which extends through an arcuate slot formed through said supporting plate, means connected to said pivot pin for actuating the toggle into made and broken positions, and the opposite end walls of said slot constituting stops against which the pivot pin engages to limit movement of the toggle in its two positions.

In witness whereof, I hereunto subscribe my name, as attested by the two subscribing witnesses.

HUBERT F. KRANTZ.
